England, assignor to Radio Electronics Lim-
ited

Application August 10, 1942, Serial No. 454,214
In Great Britain August 5, 1940

6 Claims. (Cl. 250—27)

1

The invention relates to electron multiplier apparatus primarily for dealing with ultra-high frequencies but applicable also for dealing with lower frequencies.

According to this invention an electron multiplier comprises a number of pairs of electrodes for controlling the velocity of the electrons (hereinafter referred to as velocity-controlling pairs of electrodes) disposed in the stream of electrons between a primary cathode and an anode, one or more secondary cathodes also disposed in said stream, means for generating an alternating field between the electrodes of each velocity-controlling pair, the distance apart between adjacent electrodes of successive pairs being selected in accordance with the phase relationship of their potentials, so that the time of transit of an electron is such that it passes through a succeeding field approximately at the same stage in the cycle as that when it passed through the preceding field.

The alternating fields may be applied to said pairs of velocity-controlling electrodes so that the adjacent electrodes of successive pairs are in phase and at equal potentials while the two alternating fields produced by said adjacent pairs are 180° out of phase, the spacing apart of equipotential electrodes being such as to provide a time of transit corresponding to the time of half a cycle or multiples thereof. Alternatively, the alternating field between each pair of velocity-controlling electrodes may be provided by connecting the electrodes through suitable impedances with a terminal of an alternator. In any of the arrangements referred to above, one or more secondary cathodes may be arranged between the adjacent electrodes of successive pairs.

The effect of this arrangement is that the velocity of certain electrons is increased, while others are decreased and a location will occur along the stream where a maximum density of electrons occurs.

A collector electrode is preferably disposed in the stream of electrons at the location of maximum density. The conversion of the velocity modulation into density modulation may be obtained at a following secondary cathode of the multiplier since the secondary emission is dependent upon the velocity of the electrons impinging on the secondary cathode. Alternatively, or in addition, other known means may be employed to obtain the required conversion.

Furthermore, either or both of the electrodes of a velocity-controlling pair of electrodes may be constituted by a secondary cathode, since the

2

effect of a secondary cathode is to arrest the slower velocity electrons, while the impact of the higher velocity electrons will release additional electrons.

5 The following is a description of two embodiments of the invention, reference being made to the accompanying drawing, in which—

Figure 1 and Figure 2 are diagrammatic views each showing diagrammatically an electron multiplier together with its external circuit.

10 According to the construction shown in Figure 1, the electron multiplier is provided with a primary cathode 10 and secondary electron-emitting cathodes 11, 12, 13, 14, 15 and 22. A control grid 17 is provided between the primary cathode and the first secondary cathode 11, and a final collecting anode 16 is provided at the back of the last secondary cathode 22. The primary electron stream may be modulated by a modulator 19 connected to the control grid, and the potential of the grid may be biased through one part 20 of a potentiometer which is connected at suitable tapping points along its length to the secondary cathodes. It will be seen that in front of the secondary cathode 12 is disposed a pair of velocity-controlling electrodes 21 and 18, while a second pair of velocity-controlling electrodes 23 and 24 are provided at the back of the electrode. The two electrodes 18 and 23 are both connected to one pole of an alternator 8, whereas the electrodes 21 and 24 are connected to the other pole of the alternator. The secondary cathode 12 is thus disposed in an equipotential field. The alternating fields between the electrodes 21 and 18 and between the electrodes 23 and 24 are, however, 180° out of phase. Thus, in order to effect velocity modulation, the time of transit of an electron between the electrodes 18 and 23 should be equivalent to half the time of a complete cycle of the alternating generator, or odd multiples thereof. Although the secondary cathode 12 has the effect of arresting the low-velocity electrons, the secondary electrons released by it do not upset the velocity modulation.

45 The next two secondary cathodes 13 and 14 are grouped together, and have on one side thereof a pair of velocity-modulating electrodes 24 and 25, and on the other side thereof a pair of velocity-modulating electrodes 26 and 27. Again, in this instance, the adjacent electrodes 25 and 26 of the two pairs are connected to one pole of the alternator, whereas the electrodes 24 and 27 are connected to the other pole. Similarly, the secondary cathode 15 has two pairs of velocity-controlling electrodes, one pair on each side

thereof, viz., the electrodes 27 and 28, and the electrodes 29 and 30, the electrodes 28 and 29 being connected to one pole of the generator, and the electrodes 27 and 30 being connected to the other pole. A dual antennae 7 is either connected between the electrode 30 and the two electrodes 23 and 29 or between the electrode 30 and the anode 16 as shown in the drawing. One side of the dual antennae could either be connected to the secondary cathode 22 or to the anode as shown in Figure 1. In any of these arrangements the secondary cathode 22 may operate to convert the velocity modulation to density modulation, as set out above.

In the arrangement shown in Figure 2, the 15 alternating field between the various pairs of velocity-controlling electrodes is obtained by connecting each electrode through a suitable impedance to a terminal of the alternator. The secondary cathode 31 is arranged in an equipotential field between electrodes 32, 33, which are connected through a variable impedance 34 to a terminal of the alternator 8. Velocity modulation does not take place until after this electrode. The next secondary cathode, 35, however, has a pair 20 of velocity-controlling electrodes on each side thereof, viz., the electrodes 33 and 36, and the electrodes 37 and 38. Alternating fields are created between the electrodes of each pair by reason of the fact that the electrode 33 is connected through a variable impedance 34 with the alternator, and the electrode 36 is connected through a different variable impedance 39 with 25 said alternator. Similarly, the electrodes 37 and 38 are connected through the different variable impedances 39 and 40. The secondary cathodes 41 and 42 each have a pair of velocity-controlling electrodes on each side thereof, in the one case the pairs 37, 38 and 43, 44 and in the other case, the electrodes 43, 44 and the electrode 45 and the secondary cathode 22, a further variable impedance 46 being provided between the equipotential electrodes 44 and 45 and the alternator.

In the two arrangements referred to above the velocity-controlling electrodes are shown as ordinary grids; these, however, could be replaced by secondary cathodes.

I claim:

1. An electron multiplier apparatus comprising a primary cathode, an anode, a number of pairs of velocity-controlling electrodes and at least one secondary cathode disposed between the primary cathode and anode, means for applying direct current potentials of ascending order to said primary cathode, secondary cathode and anode, means for applying an alternating field between the electrodes of each pair of velocity-controlling electrodes, the distance apart between electrodes of successive pairs of velocity-controlling electrodes being selected in accordance with the phase relationship of their potentials so that the 50 transit time of an electron is such that it passes through a succeeding field at approximately the same stage in the cycle as that when it passed through the preceding field.

2. An electron multiplier apparatus comprising a primary cathode, an anode, a number of pairs of velocity-controlling electrodes and at least one secondary cathode disposed between the primary cathode and anode, means for applying direct current potentials of ascending order to said primary cathode, secondary cathode and anode, means for applying an alternating field between the electrodes of each pair of velocity-controlling electrodes so that adjacent electrodes of successive pairs are in phase and at equal po- 65

5 tentials, while the two alternating fields produced by two adjacent pairs are 180° out of phase, the spacing apart of the electrodes being such as to provide a time of transit of an electron between equipotential electrodes corresponding to the time of odd multiples of half a cycle including a single half-cycle and to cause said electron to pass through a succeeding field at approximately the same stage in the cycle as that when it passed through the preceding field.

3. An electron multiplier apparatus comprising a primary cathode, an anode, a number of pairs of velocity-controlling electrodes and at least one secondary cathode disposed between the primary cathode and anode, an alternator arranged to apply an alternating field between the electrodes of each pair of velocity-controlling electrodes, means for applying direct current potentials of ascending order to said primary cathode, secondary cathode and anode, an impedance connected between said alternator and each pair of said velocity-controlling electrodes, the values of which impedances are selected so that the two alternating fields produced by two adjacent pairs of electrodes are 180° out of phase and the spacing apart of the electrodes of the two pairs being such as to provide a time of transit of an electron between the adjacent electrodes of two pairs corresponding to the time of an odd multiple of half a cycle including half a cycle and to cause said electron to pass through a succeeding field at approximately the said stage in the cycle as that when it passed through the preceding field.

4. An electron multiplier apparatus comprising a primary cathode, an anode, a number of pairs of velocity-controlling electrodes disposed in the stream of electrons between the primary cathode and anode, at least one secondary cathode arranged between adjacent electrodes of successive pairs of velocity-controlling electrodes, means for applying direct current potentials of ascending orders to said primary cathode, secondary cathode and anode, means for applying an alternating field between the electrodes of each pair of velocity-controlling electrodes, the distance apart between electrodes of successive pairs of velocity-controlling electrodes being selected in accordance with the phase relationship of their potentials so that the time of transit of an electron is such that it passes through a succeeding field at approximately the same stage in the cycle as that when it passed through the preceding field.

5. An electron multiplier apparatus comprising a primary cathode, an anode, a number of pairs of velocity-controlling electrodes disposed in a stream of electrons between the primary cathode and anode, at least one secondary cathode disposed between each pair of velocity-controlling electrodes, a secondary cathode immediately preceding said anode, an output circuit associated with said secondary cathode, means for applying potentials of ascending order to said primary cathode, secondary cathode and anode, means for applying an alternating field between the electrodes of each pair of velocity-controlling electrodes, the distance apart between electrodes of successive pairs of velocity-controlling electrodes being selected in accordance with the phase relationship of their potentials so that the time of transit of an electron is such that it passes through a succeeding field at approximately the same stage in the cycle as that when it passed through the preceding field.

6. An electron multiplier apparatus comprising a primary cathode, an anode, a number of pairs of velocity-controlling electrodes disposed in the stream of electrons between the primary cathode and anode, one of which velocity-controlling electrodes in each pair being formed as a secondary cathode, means for applying direct current potentials between the primary cathode and anode, means for applying an alternating field between the electrodes of each pair of veloc-

ity-controlling electrodes, the distance apart between electrodes of successive pairs of velocity-controlling electrodes being selected in accordance with the phase relationship of their potentials so that the time and transit of an electron is such that it passes through a succeeding field at approximately the same stage in the cycle as that when it passed through the preceding field,
